UNITED STATES PATENT OFFICE.

MAX HERMANN, OF TROY, NEW YORK.

MACHINE FOR FOLDING COLLARS AND CUFFS.

SPECIFICATION forming part of Letters Patent No. 234,571, dated November 16, 1880.

Application filed May 28, 1880. (No model.)

To all whom it may concern:

Be it known that I, MAX HERMANN, of Troy, in the county of Rensselaer and State of New York, have invented a new and useful Improvement in Machines for Folding Blanks for Collars and Cuffs, of which the following is a specification.

My improvements relate to machines used for folding the edges of collar and cuff blanks preparatory to sewing.

The object of the invention is to construct a machine by which the blanks may be folded, ready for being placed together, and attached by a single line of stitching.

15 My invention consists in a presser-block fitted for reciprocation to and from a fixed bed, and a spring-pressure plate fitted between the reciprocating block and bed. The pressure-block is shaped to conform to the edge of the 20 blank and also to the edge of a folding-plate, which is to be inserted with the blank beneath the presser-block. The blank and folding-plate are inserted by hand to fold the edge as the block rises, and on the return movement 25 the folded edge will be pressed to shape.

In the accompanying drawings, forming part of this specification, Figure 1 is a front elevation, partially in section, of my machine. Fig. 2 is a vertical transverse section of the 30 same on line $x x$ of Fig. 1. Fig. 3 is a plan view of the presser-block. Fig. 4 is a plan view of the folding-plate as applied to a blank. Fig. 5 represents the folded blanks as placed together for sewing. Figs. 6, 7, and 8 are views 35 illustrating the blank in different stages of the work.

Similar letters of reference indicate corresponding parts.

A is the frame of the machine, formed with 40 the bed a and fitted with the shaft b , that carries a pulley for a belt from suitable power. c is a bar, formed with pins c' at its ends, and fitted at the top of the machine in standards d , that rise from the ends of the bed a . The 45 pins c project through vertical slots in standards d , and to the pins are connected the rods e from eccentrics f on shaft b , so that by revolution of shaft b the bar c will be reciprocated. The bar c thus forms a reciprocating head, 50 having a movement to and from the bed a .

B is the presser-block, formed with end lugs,

g , and placed beneath the head c , with the lugs g projecting through the slotted standards d to retain the block in place and permit vertical movement of the same. This block B 55 is formed of metal, and hollow, with an opening at one side, fitted with a coupling for connection of a steam-pipe to admit steam for heating the block. The under side of the block is flat, and the front side is concave 60 lengthwise or curved to the shape of the edge of the collar-blank.

Between the block B and head c is fitted a curved spring-bar, l , through which the pressure of head c is exerted to force the block 65 downward, and which spring compensates for variations in thickness of the blanks. The lugs g of block B extend into the slotted ends of the rods e , so that the block will be raised by the rods. I have also shown rods h , ex- 70 tending from the under side of block B down through apertures in bed a and through flanges h' , that project from the side of frame A and serve as guides for the rods. Upon the rods h , between the guides h' and fixed collars on 75 the rods, are spiral springs i , which tend to raise the block B.

It is evident that the springs i might be dispensed with, or used alone for raising the block, instead of connecting the blocks to the 80 reciprocating rods, and in case of a foot-power machine I prefer to use the springs alone. The block may also be fixed and the bed reciprocated.

C is the pressure-plate, fitted beneath block 85 B, above bed a , and $m m$ are springs between the plate and bed, acting to throw the plate upward. The plate C conforms at its front edge to the shape of block B, and projects a short distance in front of the block to form a 90 ledge, or it may project at both sides if the machine is constructed for pressing two blanks at once.

The folding-plate, which I use in connection with the machine, is shown at k , Fig. 4, and is 95 simply a plate of metal cut to the shape of the collar-blank, but smaller, so that when laid upon the blank, as shown in said figure, the edges of the blank project the distance required for folding.

100 The operation is as follows: The shaft b being set in motion by connection to power, and

the hollow block B connected with steam-pipes, the operator, standing in front of the machine, places the plate k upon a collar-blank and lining, as shown in Figs. 4 and 6, and holds them by a thumb and finger at the ends. Then, by placing the edge of the blank with the plate against the face of block B, by a downward movement of the hand, the edge of the blank is bent upward and gathered, as shown in Fig. 7. Then, as the block B rises, the edges of the plate and blank are slipped between the block B and plate C, which completes the folding, and on the downward movement of block B the folded edge is pressed. The plate and blank may then be removed and the plate placed on another blank. The projecting edge of the pressure-plate C forms a ledge which arrests the folding-plate and blank, and serves to hold them with the edge of the blank raised, as in Fig. 7, until the block has risen, and the tension of the springs m is sufficiently released to allow insertion of the blank beneath the block. The pressure-plate thus serves to hold the folded edge until the required pressure is given upon the table a at the completion of the downward movement. After the blanks are folded as described they are to be placed together, as shown in Fig. 5, for sewing down the folded edges. If desired, the block B may be formed with a side extension, as at g', Fig. 3, of a form for

pressing the end of the collar. The edge will be pressed by giving a side movement to the blank and plate k after the front edge is pressed, so that at the next descent of the block the end will be pressed. This will save handling of the blanks twice.

Having thus described my invention, I claim as new and desire to secure by Letters Patent—

1. In machines for folding blanks for collars and cuffs, a reciprocating presser-block, B, spring-pressure plate C, and fixed bed, combined for operation, substantially as shown and described.

2. In machines for folding blanks for collars and cuffs, in combination with the fixed bed, the presser-block B, fitted for reciprocation to and from the bed, and the presser-plate C, placed between the block and bed, and provided with springs for forcing it toward the presser-block, substantially as and for the purposes set forth.

3. The hollow presser-block B, having its front face curved to the shape of the blank, combined with the reciprocating head e, spring-plate C, and fixed bed a, substantially as and for the purposes set forth.

MAX HERMANN.
